UNITED STATES PATENT OFFICE.

JAMES W. BRUNDAGE, OF AKRON, OHIO, ASSIGNOR TO THE MILLER RUBBER COMPANY,
OF AKRON, OHIO, A CORPORATION OF OHIO.

WASHER SETTING.

Application filed March 24, 1924. Serial No. 701,297.

To all whom it may concern:

Be it known that I, JAMES W. BRUNDAGE, a citizen of the United States of America, and a resident of Akron, in the county of 5 Summit and State of Ohio, have invented certain new and useful Improvements in Washer Settings, of which the following is a full, clear, and exact description.

It is customary to place in rubber heels 10 washers adapted to act as abutments for the heads of the nails with which the heel is to be secured to the shoe and it is customary to insert these washers into the heels by placing them on pins positioned within the cavities of the mold in which the heels are cured. 15 Placing these washers upon these pins by hand not only subjects the operator to the likelihood of being burned from the hot mold but also consumes an appreciable 20 amount of time during which the mold is useless for its principal purpose. My invention provides mechanical means for placing these washers in position upon the pins. In the drawings accompanying this specification 25 and forming a part thereof I have shown, for purposes of illustration, one form which my invention may assume. In these drawings:

Figure 1 is a longitudinal section through 30 a portion of the device.

Figure 2 is a section similar to Figure 1 showing the device in a second operating position.

Figure 3 is a section on the line 3-3 of 35 Figure 2.

Figures 4 and 5 are fragmentary sections showing in more detail the manner in which the transfer of the washer is performed, while

Figures 6 and 7 are sections showing in 40 similar detail the manner in which the second transfer is performed.

The device herein shown comprises a base 11 carrying a pair of transverse rods 12 on 45 which is reciprocably mounted a frame 13 which in turn carries a pair of transverse shafts 14 and 15 each provided with two cam disks 16 arranged to movably support, within the open upper end 17 of the frame 13, a plate 18 adapted to itself support a lifting plate 19 of a size to be received within 50 the open upper end 17 of the frame 13 and provided with a plurality of pins 20 reciprocable through apertures 21 in a locating plate 22 also of a size to be received within

the open upper end 17 of the frame 13 but provided with suitable lugs 23 arranged to cooperate with recesses 24 in the walls of the frame 13 to limit the insertion of the plate 22 into the frame 13 and maintain the plate 22 elevated and spaced from the lifter plate 19. The frame 13 is also provided at its rear edge 25 with a trough 26 pivoted to the frame 13, adapted to maintained in the position shown in Figure 2 by engagement with 60 the frame 13, and arranged to be swung about its pivot 27 into the position shown in Figure 1 in which the contents of the trough have been dumped upon the plate 22. The two shafts 14 and 15 are connected to operate as a unit by means of levers 28 and 29 secured to the shafts 14 and 15 respectively and a link 30 extending between the levers 28 and 29 and the shafts 14 and 15 are operated by means of a hand lever 31 secured to 65 the shaft 14. Means (not shown) are provided for transversely oscillating the entire frame 13 and the plate 22 is provided with a plurality of circular depressions 32 positioned with the same spacing as the mold pins on which the washers are to be placed and each adapted to receive and hold a washer 33.

In operating this portion of the device the trough 26 is swung into the position shown 80 in Figure 1 and the frame 13 oscillated to cause the washers 33 to gradually travel down the inclined surface of the plate 22 and during this travel to seat in the depressions 32 which are arranged to each hold but one 85 washer 33 and to hold that washer only when it is concave upwardly. By the time this action is completed and the surplus washers have traveled downwardly across the plate 22 it is found that invariably one washer has lodged right side up in each of the depressions 32 and accordingly that the plate 22 carries a set of washers arranged in exactly the arrangement of the mold pins on which the washers are to be positioned. 90

There is then inserted within a groove 34 in the upper portion of the side and rear walls 35 and 36 of the frame 13 a transfer plate 37 secured against upward movement 95 by the overlying portion of the frame 13 and provided with a plurality of apertures 38 arranged to register with the depressions 32 in the plate 22 and each provided with a rubber bushing 39 secured in its aperture 38 by means of over and under lying 100

110

flanges 40 and 41 and provided interiorly with ribs 42 and 43 together forming an annular recess 44 adapted to receive the washer 33 to thereafter releasably hold the washer 33 against movement from the plate 37 in any direction. The washers 33 are moved into the plate 37 by means of the pins 20 as these pins 20 are actuated through the lifter plate 19 by the action of the cams 16 upon the supporting plate 18 when the lever 31 is swung forwardly into the position shown in Figure 2.

After this action has occurred the transfer plate 37, carrying with it the washers 33, is removed from the frame 13 ready for use when the mold next comes from the vulcanizing press. At that time the transfer plate 37 is placed upon the mold with the apertures 38 of the transfer plate 37 registering with the pins 45 of the mold 46 and a plurality of cylindrical pins 47, carried by an expulsion plate 48 and having the same relative spacing as the mold pins 45, are advanced against the washers 33 after which the expulsion plate 48 is depressed to cause the various pins 47 to force the washers 33 from the annular recesses 44 of the bushings 39 down on to the mold pins 45 in position for incorporation into the heels. The expulsion plate 48 is then removed from the transfer plate 37 and the transfer plate 37 from the mold 46 leaving the mold ready for use.

It will be understood that the surplus washers passing over the plate 22 may be collected in any suitable receptacle or may be automatically returned to the trough 26, that the frame 13 may be transversely oscillated in any suitable manner as by direct manual force or by a cam or eccentric mechanism operating either manually or by power, that power means may be employed to operate the shafts 14 and 15 and cams 16, that power means may be employed to depress the expulsion plate 48, and that the plate 37 may be registered with the mold 46 in any suitable manner as by means of dowel pins carried by one part and registering with recesses in the cooperating part. It will be understood by those skilled in the art that a number of transfer plates 37 may be provided for each pin spacing and may be filled and used as a storage or reservoir, that the lifting plate 19, locating plate 22, transfer plates 37, and expulsion plate 48, will all be duplicated for each different pin spacing, that in changing from one pin spacing to another the lifting plate 19 and locating plate 22 of the one spacing will merely be lifted from the frame 13 to afford facilities for the lifting plate 19 and locating plate 22 of the second spacing, that the arrangement herein shown admits reasonable variation in the thickness and contour of the washers and in the position of the mold pins either in different

molds supposed to be identical or from time to time in the same mold, and that the use of the apparatus herein shown and described not only eliminates the possibility of burning the operator but also eliminates the time required for placing the washers in position upon the mold pins. It will also be obvious to those skilled in the art that the particular embodiment of my invention herein shown and described may be variously changed and modified without sacrificing the advantages of my invention or departing from the spirit thereof and it will therefore be understood that the disclosure herein is illustrative only and that my invention is not limited thereto. 70 75 80

I claim:

1. In a washer setting device, arranging means adapted to hold a plurality of washers in a definite relative spacing, transfer means adapted to receive said washers and support 85 said washers in such spacing, and a plurality of pins adapted to engage said washers and move said washers from said arranging means to said transfer means.

2. In a washer setting device, a transfer plate having a plurality of apertures, each adapted to receive a washer and each provided with resilient washer engaging means having spaced ribs to receive the edges of a washer therebetween, and releasably hold 95 said washer against movement in any direction.

3. In a washer setting device, a transfer plate having a plurality of apertures each adapted to receive a washer and each provided with a rubber bushing having a pair of ribs spaced to receive said washer therebetween to thereby releasably hold said washer against movement in any direction. 100

4. In a washer setting device, a transfer plate having a plurality of apertures each adapted to receive a washer and each provided with a rubber bushing to releasably hold said washer. 105

5. In a washer setting device, a locating plate adapted to hold a plurality of washers in a definite relative spacing, lifting means comprising a plurality of pins adapted to be moved through apertures in said locating plate to lift said washers above said locating plate while maintaining said spacing, a frame removably supporting said locating plate and said lifting means, means carried by said frame adapted to deposit a multiplicity of washers on said locating plate, 115 and means arranged to oscillate said locating plate to cause said washers to travel thereover. 120

6. In a washer setting device, a locating plate adapted to hold a plurality of washers in a definite relative spacing, lifting means comprising a plurality of pins adapted to be moved through apertures in said locating plate to lift said washers above said locating plate while maintaining said spacing, 125 130

a frame removably supporting said locating plate and said lifting means, and means carried by said frame to operate said lifting means when said lifting means are in position in said frame.

5. 7. In a washer setting device, a locating plate adapted to hold a plurality of washers in a definite relative spacing, lifting means comprising a plurality of pins adapted to

be moved through apertures in said locating plate to lift said washers above said locating plate while maintaining said spacing, and a frame removably supporting said locating plate and said lifting means.

10. In testimony whereof, I hereunto affix my 15
signature.

JAMES W. BRUNDAGE.
